Inventor.
Jacob Kaufmann,
By Jas. C. Nobusmith
Attorney.

UNITED STATES PATENT OFFICE.

JACOB KAUFMANN, OF ELKINS PARK, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

HEDDLE FRAME.

Application filed March 10, 1923. Serial No. 624,170.

To all whom it may concern:

Be it known that I, JACOB KAUFMANN, a citizen of the United States, residing at Elkins Park, in the county of Montgomery and State of Pennsylvania, have invented certain new and useful Improvements in Heddle Frames, of which the following is a specification.

My invention relates to heddle frames for looms, and it has particular relation to the provision of improved means in such heddle frames for securing the heddle supporting bars against displacement in the frame.

In the construction of heddle frames in which the end members, as well as the top and bottom bars, are made of strips of wood or similar material, considerable difficulty is ordinarily experienced in the provision of suitable and efficient means for securing the heddle supporting bars in proper position in the frame, particularly where the frame is made as thin as possible, as is often required where the space is limited.

The principal object, therefore, of my present invention is to provide a heddle frame, in which the end members, as well as the top and bottom bars, are made of relatively thin strips of wood or similar material, having improved means for securing the heddle supporting bars in place, which will be inexpensive, yet efficient, and which will require a minimum of labor in the construction, arrangement and assembly thereof.

The nature and characteristic features of my invention will be more readily understood from the following description, taken in connection with the accompanying drawings forming part hereof, in which:

Figure 1 is a side elevational view of a heddle frame embodying the main features of my present invention;

Fig. 2 is a fragmentary detail view, enlarged, partly in section, of one corner of the heddle frame shown in Fig. 1, the same illustrating more clearly the details of the construction and arrangement of the improved means for securing the heddle supporting bar in place; and

Fig. 3 is an end elevation of the portion of the structure shown in Fig. 2.

Referring to the drawings, the heddle frame proper preferably comprises top and bottom bars 5 and end members 6, all of which are preferably made of relatively thin

strips of wood, the same being united to each other at the corners, by suitable mortises or other preferred construction to provide a rigid frame.

The heddle supporting bars 7, with the heddles 8 mounted thereon in the usual manner, are mounted in the frame having their end portions extending through slots 9 extending through the end members 6. The ends of the heddle supporting bars 7 project beyond the outer marginal edge of the end members 6 and are preferably apertured, as at 10, in said extending portions.

The securing device proper comprises a member 11, preferably made of spring steel wire. One end of the member 11 has a bent over extension 12, preferably provided with a sharpened end 13, so that the same may be forced or driven into the end member and there held by frictional engagement as clearly shown in Fig. 2 of the drawings. The end members 6 may be preliminarily bored or not for the reception of the extension 12 of the member 11, according to the nature of the material of the end members 6, as will be readily understood. Adjacent

the extension 12 of the member 11 is a portion 14 arranged substantially at right angles to the extension 12 and adapted to be seated in a recess 15 in the outer surface of the end member 6, the recess 15 extending along the outer surface of the end member 6 a sufficient distance for the reception of the portion 14. The material of the member 11 is then bent outward at the end of the portion 14, as shown at 16, and thence extends adjacent the outer surface of the end member 6, as at 17, finally terminating in a hook-like portion 18 which is adapted to engage the aperture 10 in the projecting end of the heddle supporting bar 7, it being understood that, for the purpose of effecting said engagement of the hook-like portion 18 with the aperture 10, the free end of the member 11 may be sprung, from the position shown in dotted lines in Fig. 2 of the drawing to that shown in full lines, into operative engagement, as aforesaid, with the aperture 10 of the heddle bar 7.

It will be seen that there is thus provided a simple and efficient means for securing the heddle supporting bar against longitudinal displacement in the frame, which is so constructed and arranged as to require a

minimum of labor in the construction and assembly thereof in the frame, but which will be quite efficient in its action. By seating the portion 14 of the securing member 5 11 in the recess 15, the member 11 will be maintained against rotation about the axis which would otherwise be afforded by the portion 12 which is driven into the end member 6 and which is retained therein by frictional engagement. Thus the member 11 10 will always be maintained in such position that no part thereof will be permitted to extend beyond the side surfaces of the frame, and will thereby preclude the possibility of any portion of the securing member 11 fouling with adjacent frames or any portions thereof, during the reciprocation 15 of the frames in the loom.

Having thus described the nature and 20 characteristic features of my invention, what I claim as new and desire to secure by Letters Patent is:

1. A heddle frame comprising top and bottom bars and end members, heddle supporting bars mounted in said frame extending through slots in the end members and having their ends projecting beyond the outer margins of the end members and having apertures provided in said projecting 25 portions, securing devices each adapted to engage one of said projecting end portions of the heddle supporting bar and comprising a member made of spring wire having one end thereof extending into the material of the end member and being retained therein by frictional engagement, said member having a spring-like extension, the free end of said extension being provided with a hook-like portion adapted to engage the aperture in the heddle supporting bar, and means for preventing rotative movement of said securing member about the portion thereof which extends into the end member of the frame.

2. A heddle frame comprising top and bottom bars and end members, heddle supporting bars mounted in said frame extending through slots in the end members and having their ends projecting beyond the outer margin of the end members and having apertures provided in said projecting portions, securing devices mounted on the outer marginal edges of said end members each adapted to engage one of said projecting end portions of the heddle supporting bar and comprising a member made of spring wire having one end thereof extending into the material of the end member and being retained therein by frictional

engagement, said member having a spring-like extension, the free end of said extension being provided with a hook-like portion adapted to engage the aperture in the heddle supporting bar, and means for preventing rotative movement of said securing member about the portion thereof which extends into the end member of the frame.

3. A heddle frame comprising top and bottom bars and end members made of thin flat strips, heddle supporting bars mounted in said frame extending through slots in the end members and having their ends projecting beyond the outer margins of the end members and having apertures provided in said projecting portions, securing devices mounted on the outer marginal edges of said end members each adapted to engage one of said projecting end portions of the heddle supporting bar and comprising a member made of spring wire having one end thereof extending into the material of the end member and being retained therein by frictional engagement, said member having another portion thereof seated in a recess in the outer marginal edge of said end member to prevent rotative movement of said securing device, and having a spring-like extension, the free end of said extension being provided with a hook-like portion adapted to engage the aperture in the heddle supporting bar.

4. A heddle frame comprising top and bottom bars and end members made of thin flat strips, heddle supporting bars mounted in said frame extending through slots in the end members and having their ends projecting beyond the outer margins of the end members and having apertures provided in said projecting portions, securing devices mounted on the outer marginal edges of said end members each adapted to engage one of said projecting end portions of the heddle supporting bar and comprising a member made of spring wire having one end thereof extending into the material of the end member and being retained therein by frictional engagement, said member having an adjacent portion thereof seated in a recess in said end member to prevent rotative movement of said securing device, and having a spring-like extension, the free end of said extension being provided with a hook-like portion adapted to engage the aperture in the heddle supporting bar.

In testimony whereof, I have hereunto signed my name.

JACOB KAUFMANN.
